(57) **CLAIM**

The ornamental design for a cockpit center console, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a cockpit center console; FIG. 2 is a front view thereof, the back view forming no part of the claimed design;

FIG. 3 is a first side view thereof;

FIG. 4 is a second side view thereof; and,

FIG. 5 is a top view thereof, the bottom view forming no part of the claimed design.

The broken lines illustrate structure and environment that form no part of the claimed design.
